UNITED STATES PATENT OFFICE.

FREDERICK M. BOWERS, OF CHESTER, PENNSYLVANIA.

ELECTRODE HOLDER.

Application filed October 17, 1927. Serial No. 226,634.

This invention relates to clamping and holding means and more particularly to a device of this character for holding electric-welding electrodes.

5 The object of my invention is to provide an improved electrode holder which will positively grasp and hold an electrode; to provide means for conducting the welding current to and through the electrode without 10 loss or heating; and to provide improved means for permitting the electrode to be inserted and for releasing it from the holder.

15 My invention consists in the construction and arrangement of parts hereinafter described and claimed and shown in the accompanying drawings, in which

Figure 1 is a plan view of a device incorporating the invention.

Figure 2 is a side view of the illustration 20 shown in Figure 1.

Figure 3 is a section through the device, some parts shown in full.

Figure 4 is a section on the line 4—4 of Figure 1, some parts shown in full.

25 Figure 5 illustrates a form of trigger arrangement, and its relation to some of the other elements of the combination; and

Figure 6 is a section through the line 6—6 of Figure 1 and a view looking toward the 30 handle from the clamping end of the device.

Figure 7 is a fragmentary longitudinal section through the gripping jaws of a modified form of electrode holder, and

Figure 8 is a cross-section therethrough 35 taken on line 8—8 on Figure 7.

Considering Figures 1 to 6 simultaneously, similar designations referring to similar parts, numeral 7 represents a removable handle, made of fibre, bakelite, or other suitable 40 insulating material, frictionally mounted on collar 8. The handle is preferably reduced at the conductor receiving end, to snugly accommodate conductor 24 leading to terminal 12.

45 One end of each of a pair of oppositely faced spring jaws 11 is secured to terminal 12. The jaws are bent adjacent their free ends, as shown at 14, and the ends, beyond the bend, form parallel normally contacting parts provided with grooves 15 adapted to grasp and hold an electrode. The jaws should be sufficiently stiff to exert material pressure upon the electrode thereby insuring a firm grasp of the electrode and perfect electrical contact.

55 To insure this firm grip of the jaws without

making them needlessly heavy, I confine them approximately midway of their length by collar 8 secured to handle 7 which prevents any yielding in its rear and exerts a pressure tending to reinforce the pressure of the 60 springs and hold the jaws more firmly in contact. The jaws preferably taper slightly from bend 14 to the point at which the collar is attached for convenience in positioning the collar. An insulating guard 9 of materially larger diameter than handle 7 is 65 preferably disposed between the handle and collar 8. This serves to protect the operator from heat radiating from the jaws and permits the holder to be rested upon a deck or 70 other surface without danger of making an electrical contact.

In the preferred construction the gripping ends of the jaws are so firmly held in contact that mechanical means for forcing them apart 75 are required. For this purpose I provide the jaws with interior and opposite arcuate grooves 11^a and provide a separating or prying rod 21, extending between the jaws, the heel end of which is pivotally mounted upon an eccentric pin 22 extending between two disks 18 which are fixed to a shaft 17 rotatably mounted in jaws 11. A trigger 19, also fixed to shaft 17, extends through a notch 20 in handle 7 and is provided with an insulated 80 handle 19^a. The free end of rod 21 preferably carries a ball 23 seated between grooves 11^a and of a diameter sufficient, when the ball is forced forwardly in the groove to press the jaws apart sufficiently to permit them to 85

freely receive an electrode. Actuation of the trigger in one direction forces the jaws apart and actuation in the other direction permits them to close. The trigger is so formed that after it is actuated to open the 90 jaws, the jaws will be held in open position until the trigger is actuated in reverse direction thereby relieving the operator from the necessity of holding the trigger while inserting the electrode. While I prefer the 95 ball and groove construction, it is obvious that any construction which will permit the prying rod to exert wedging action upon the jaws sufficient to open them to the desired extent will serve the purpose of the ball and 100 groove.

The holder is assembled by drawing the conductor terminal 12 through handle 7, placing the terminal and the prying rod with its connections thereover with shaft 17 ex- 110

- tending into an aperture in the jaw, placing the other jaw over the parts thus far assembled and riveting or otherwise securing the jaws to terminal 12, drawing the conductor 5 terminal, with the jaws, disks etc., back into the handle, slipping guard 9 over the hub, sliding collar 8 into position with its hub within handle 7, and securing the handle to the hub by means of insulating screw 10.
- 10 This construction provides for a firm grip of the jaws upon the electrode; a continuous path for the electric current without loss by reason of moving parts or joints; an insulating handle having a minimum of contact 15 with current carrying parts and providing a maximum circulation of air between the handle and the current carrying parts; means, insulated from the remaining part, for releasing the electrode from the jaws, thus 20 giving the operator further security against electrical shocks, and means whereby the holder may be rested upon a deck or other support without danger of making an electric circuit therethrough.
- 25 Figures 7 and 8 show a form having replaceable jaw pieces in which main jaws 11^a are cut away at 26 to provide an offset portion for accommodating jaw pieces 27 which are held in position by flanges 28 overlapping 30 the edges of jaws 11^a and by rivets 29 preferably formed integral with jaw pieces 27 and extending through suitable apertures in jaws 11^a; the ends of rivets 29 being peened over in the usual manner. Jaw pieces 27 are 35 provided with notches 15^a aligning in pairs which are adapted to grip electrodes of various sizes. When the corners of notches 15^a or other parts of the jaw pieces become worn or defective, the heads of rivets 29 may be 40 cut off and new jaw pieces riveted in place, thus lengthening the life of the electrode holder.

It will be understood that the various elements of the combination may be modified 45 and altered, and that the fundamentals disclosed may be applied and utilized in a plurality of arrangements. I, therefore, do not limit myself to the precise features of construction illustrated and described, but consider myself at liberty to use any combination 50 coming within the scope of the appended claims.

I claim:

1. An electrode holder including a pair of jaws each having a groove on its inner side, the jaws being arranged within the holder to make clamping contact with each other at the ends adjacent the grooves, a prying rod within the holder and between the jaws normally free from the contacting portions of the jaws, a handle and insulating means in combination therewith for protecting an operative of the holder from current adapted to be supplied to the jaws, the means including 65 a trigger for operating the rod to slide

within the grooves to pry the jaws apart, the jaws returning to normal contact under the control of the trigger, the trigger being arranged to assume one portion for keeping the jaws open regardless of pressure on the 70 trigger.

2. An electrode holder including a pair of opposed spring jaws spaced apart at one end and normally in contact at the other end; a conductor terminal secured between the 75 spaced ends of the jaws; a prying rod disposed between and adapted to open the jaws, and means for actuating the prying rod.

3. An electrode holder including a pair of opposed spring jaws spaced apart at one end 80 and normally in contact at the other end; a conductor terminal secured between the spaced ends of the jaws; a prying rod disposed between and adapted to open the jaws; means for actuating the prying rod, and a 85 tubular insulating handle enclosing the fixed end of the jaws, the conductor terminal and operating means for the prying rod.

4. An electrode holder including a pair of opposed spring jaws spaced apart at one end 90 and normally in contact at the other end; a conductor terminal secured between the spaced ends of the jaws; a shaft extending between the spaced ends of the jaws; a pair of disks fixed to the shaft; an eccentric pin 95 between the disks; a prying rod having one end pivotally connected with the pin and having its free end formed to wedge the contacting ends of the jaws apart, and an insulated trigger fixed to and adapted to rotate 100 the shaft.

5. An electrode holder including a pair of opposed spring jaws spaced apart at one end and normally in contact at the other end; a conductor terminal secured between the 105 spaced ends of the jaws; a shaft extending between the spaced ends of the jaws; a pair of disks fixed to the shaft; an eccentric pin between the disks; a prying rod having one end pivotally connected with the pin and having 110 its free end formed to wedge the contacting ends of the jaws apart, and a tubular insulating handle enclosing the fixed end of the jaws, the conductor terminal and the disks.

6. An electrode holder including a pair of opposed spring jaws spaced apart at one end and adapted to grasp an electrode at the other end, the jaws being provided with opposed grooves adjacent their free ends; a conductor terminal secured between the spaced ends of the jaws; a prying rod disposed between the jaws and provided with a spherical member normally resting between the grooves and adapted, when the prying rod is actuated, to force the free ends of the jaws 125 apart, and means for actuating the prying rod.

7. An electrode holder including a pair of opposed spring jaws spaced apart at one end and adapted to grasp an electrode at the other 130

- end; a conductor terminal secured between the spaced ends of the jaws, and a collar embracing the jaws, disposed between their fixed and free ends, and adapted to press the free ends into engagement. 5
8. An electrode holder including a pair of opposed spring jaws spaced apart at one end and adapted to grasp an electrode at the other end; a conductor terminal secured between 10 the spaced ends of the jaws, a prying rod disposed between and adapted to open the jaws; eccentric means for actuating the prying rod; a trigger for actuating the eccentric means; an insulating handle on the trigger; an insulating handle enclosing the spaced ends of the 15 jaws, the conductor terminal and the eccentric means, and having a notch through which the trigger handle extends; a collar, having a hub secured within the end of the insulating 20 handle, adapted to press the free ends of the jaws into engagement, and an insulating guard disposed on the hub of the collar and in contact with the end of the insulating handle.
9. An electrode holder including a pair of opposed spring jaws spaced apart at one end and adapted to grasp an electrode at the other end, a conductor terminal secured between the spaced ends of the jaws; a shaft extending between the spaced ends of the jaws; a 25 pair of disks fixed to the shaft; an eccentric pin between the disks; a prying rod having one end pivotally connected to the eccentric pin and having its free end adapted to press the free ends of the jaws apart; a trigger 30 fixed to the shaft; an insulated handle for the trigger; an insulating handle enclosing the spaced ends of the jaws, the conductor terminal and the disks; a collar embracing the jaws, adapted to press their free ends into engagement, and having a hub secured within the end of the insulating handle, and an insulating guard disposed on the hub between the collar and the insulating handle. 35
- In testimony whereof I have signed my 40 name to this specification.

FREDERICK M. BOWERS.
